UNITED STATES PATENT OFFICE

1,952,914

PRINTING MACHINE

Joseph S. Duncan and Henry E. Hubbard, Chicago, Ill., assignors to Addressograph Company, Chicago, Ill., a corporation of Delaware

Original applications August 12, 1927, Serial Nos. 212,424 and 212,425. Divided and this application January 26, 1931, Serial No. 511,266

10 Claims. (Cl. 101—47)

This application is a division of our applications Serial No. 212,424, filed August 12, 1927, Patent No. 1,792,149, patented February 10, 1931, and Serial No. 212,425, filed August 12, 1927, Patent No. 1,792,150, patented February 10, 1931.

This invention relates to machines for printing addresses or other matter on periodical publications or the like and the salient object is to provide a novel automatic machine wherein a series 10 of printing devices bearing address forms may be successively moved into printing position and wherein the periodicals or the like may be successively fed into printing position whereby an address may be printed upon each periodical.

15 Other objects are to feed the individual printing devices into printing position and to automatically determine whether or not a printing device is to be printed so that impressions may be made from some of the printing devices while others

20 will be as it is termed skipped; to interrupt the feed for the periodicals when a printing device is to be skipped; and to retain a printing device from which an impression is to be made in printing position in the event no periodical is fed.

25 Heretofore periodicals have usually been fed into machines of the character to which this invention appertains by hand or they have been fed into the machine automatically from a stack disposed adjacent the receiving end of the machine. The hand operation is expensive and requires one or more operators. The automatic stack feed time operation does not always prove satisfactory in that more than one periodical is sometimes fed into the machine thereby preventing proper operation. It is therefore a still further object to provide a novel feeding mechanism which will automatically feed only one periodical at a time into the machine and which will be positive and constant in operation.

30 Still further objects are to provide intermittently operating traveling chains for feeding the periodicals to the machine, to feed the periodicals into printing position in the machine after movement thereof into the machine, and to provide safety devices which will interrupt operation of the machine in the event any of the parts fail to operate properly.

In the selected embodiment of the invention 35 illustrated in the accompanying drawings,

Fig. 1 is a front elevation of the machine; Fig. 1a is an enlarged fragmentary detail view; Fig. 2 is a top plan view; Fig. 3 is a longitudinal sectional view taken substantially on the line 3—3 on Fig. 2;

Fig. 4 is a detail view of a clutch used on the main drive shaft of the machine;

Fig. 5 is a longitudinal sectional view taken substantially on the line 5—5 on Fig. 2;

Fig. 6 is a side elevation of the printing device 40 safety arrangement;

Fig. 7 is a fragmentary plan view of the device illustrated in Fig. 6;

Fig. 8 is a front elevation thereof;

Fig. 9 is a sectional view taken on the line 45 9—9 on Fig. 2;

Fig. 10 is a detail plan view of the receiving end of the machine showing the feeding mechanism;

Fig. 11 is a detail rear view, partly in section, 50 showing the feed operating mechanism and the selecting mechanism therefor; and

Figs. 12 and 13 are detail sectional views taken longitudinally through the feeding mechanism.

In the accompanying drawings, 1 is a suitable 55 frame in which a drive shaft 2 is journaled having a flywheel 3 on one end thereof driven by suitable means such as an electric motor (not shown). A handle 4 may be provided on the flywheel for operating the machine by hand when so desired. 60 A collar 5 rotates with the shaft and is rigidly mounted on the shaft 2 adjacent the flywheel. A pawl 6 on the collar is arranged adjacent the flywheel and is adapted to engage a slot in the shaft 2. The pawl 6 operates with the arm 8 65 (Fig. 4) which forces it into or out of the slot, a spring 9 normally holding the pawl inwardly. This mechanism forms the main clutch 10 that is clearly illustrated in Fig. 4. A gear 11 on the shaft 2 meshes with a gear 12 on the cam shaft 13 to operate the mechanism for feeding periodicals one at a time into the machine. The cam shaft 13 extends transversely across the machine and the ends thereof are mounted in suitable journals 14 and 15 in the feed mechanism casing 70 16. On the cam shaft 13 is a main gear 17 that drives a gear 18 (Fig. 1) mounted on the shaft 19 of the belt conveyor through the idlers 20 and 20' (Fig. 1) journaled in the side of the casing 16. The wide idler gear 21 (Fig. 5) 75 mounted on the stub shaft 23 is meshed with both gears 17 and 22. The gear 22 is fast on the shaft 26. Pulleys 27 spaced on shaft 26 are free to rotate with the shaft. Spaced from shaft 26 is a shaft 28 carrying pulleys 29. A pair 80 of belts 30, 30' are directed about these pulleys as shown in Fig. 2. The pulleys are positioned and are of sufficient diameter to allow the bottom edges of the belt to just clear the top of the machine and render sufficient friction to al-

85 90 95 100 105 110

low the article to be printed to be carried longitudinally across the machine. As shown in Figs. 1 and 2, the shaft 28 is supported by uprights 31 mounted on the frame and these uprights have 5 their bases grooved at 32 to permit longitudinal adjustment thereof. A gripper roll rocker 35 is mounted on shaft 34 (Fig. 5) supported by a hanger 33 connected to the casing 16 and extending downwardly therefrom. A pair of juxtaposed arms 36 rigidly formed on the rocker 35 carry a shaft 37. A lever 38 is pivotally mounted on this shaft and carries a roller 39 riding on a cam 40 fixed to shaft 13. A spring 41 attached to the upper end of lever 38 holds roller 15 39 against cam 40 and rotation of the cam moves lever 39 rectilinearly, which motion is transmitted to gripper roll rocker 35. Arms 42 on rocker 35 support a shaft 43 on which the gripper rolls 46 are mounted. A shaft 47 mounted in 20 the frame carries a gear 48 driven from the main gear 17 through idler gears 45 and 45' (Fig. 1). Feed rollers 50 are fast on shaft 47 opposite the gripping rollers 46. The rollers 46 and 50 are driven to rotate in opposite directions so that 25 when the gripper roll rocker reciprocates toward the feed roller shaft 47 the article to be printed is grasped or clamped between the rollers and fed into the machine. In order to provide positive feeding of the periodical or other article to 30 be printed, a pneumatically operated feed is provided comprising a rockable hollow rod or sucker bar 51 having one end pivotally connected to a valve casing and the other end connected to the side of casing 16 by an arm 53 that is free to travel in a slot 54 in the casing (Fig. 1). Means (such as an air compressor which is not shown) are provided for creating a vacuum in the sucker bar. On the stud 55 (Fig. 3) extending inwardly from casing 16 are two levers 56 and 57. The 35 sucker bar 51 has open ends 51' movable between the shafts 43 and 47 to engage forward marginal edge portions of the bottom periodical of the stack to pull it downwardly and partly around the feed roller so that the gripper roller may 40 clamp this bottom periodical against the feed roller to withdraw the bottom periodical from the stack. While the sucker bar is thus operating the fingers 65, to be described, are sunk away from the stack and after the sucker bar has pulled 45 the front portion of the periodical downwardly the fingers again engage the stack to prevent other periodicals from being affected while the magazine is being fed away. A pneumatic valve 50 66 (Fig. 3) in the valve casing is timed to create suction when the feed roller moves toward the periodicals and upon reverse movement this valve shuts off the sucking action and releases the grip on the periodical at approximately the 55 same time the rollers 46 and 50 engage the periodical to carry it into printing position. The periodicals are arranged at the right hand end of the machine as viewed in Fig. 1. To feed the periodicals a chain feed shaft 153 (Fig. 10) is juxtaposed to the feed roller shaft and carries 60 a plurality of sprockets 154 and is rotated by a ratchet 155 fixed to one end thereof. Endless chains 156 are arranged on these sprockets and connect the chain feed shaft with another shaft (not shown) to move the chain along the table 65 157 to carry periodicals stacked thereon to feeding position. A bell crank 158 is loosely mounted on the chain feed shaft 153 and carries mechanism to rotate this shaft. One arm (Fig. 11) of the bell crank has a stud 160 fixed thereto to 70 which one end of a link 161 is pivotally connected, 75

The other end of this link is pivotally connected to a stud 162 fastened to the gear 12. A pawl 163 is pivotally connected to the arm 164 of the bell crank for operating the ratchet. A spring 165 has one end connected to the pawl and the other connected to a lug 166 on the bell crank for normally holding the pawl against the ratchet. The cam shaft 13 has a cam 167 rigidly fastened thereto which operates against a roller 168 mounted on a cam lever 169 to reciprocate the cam lever. The upper end of the cam lever is pivotally connected to the feed control rocker 170 and reciprocates the same. A spring 171 normally holds the cam lever in operative position against the cam. The feed control rocker 170 (Figs. 11, 12 and 13) has downwardly disposed feed control fingers 65 rigidly connected thereto and against which a periodical strikes as it is being fed into the machine. Pressure against these fingers causes movement of the feed control rocker which is transmitted to the cam lever 169. When the feed control rocker is moved inwardly, the roller 168 is moved a short distance away from the cam 167 so that the cam only 80 works on the roller at certain points and gauges 85 the distance the arm 173 is to travel in operating the pawl 163. When the feed control fingers are moved inwardly substantially the full distance of this inward travel, the roller 168 is 90 entirely removed from the cam 167 and when no 95 movement is transmitted to the arm 173, the pawl is held away from the ratchet. To prevent a periodical from pushing the feed control fingers too far inwardly and prevent action of the pawl on the ratchet, a plurality of downwardly disposed 100 stop fingers 145 are fixed on the frame in front of the feeding end of the machine to limit this feed of the periodical so that the pawl may be free to work the ratchet thus assuring proper feed of periodicals into the machine. When the 105 periodicals are fed staggardly into the machine and while the feed control rocker reciprocates, the feed control fingers determine the movement of the arm 173 which controls the movement of the chain feed shaft for gauging the proper movement of the chains so that the periodicals will be 110 continuously and properly fed into the machine. The sucker bar is timed so that on its forward movement there is a suction in the bar for assisting in pulling the periodical into the machine 115 and then release the periodical at the proper time by shutting off the suction. The lowermost periodicals should normally abut against the stationary stop fingers 145. If the lowermost periodicals do not abut against the fingers the oscillating feed control or feeler fingers 65 will move 120 to the left (Fig. 12) to make contact with the front edges of the said periodical and the chain will operate to feed the lowermost periodical to the right (Fig. 12) into contact with the stationary fingers 145. Thus, the bottom periodical is positioned to be pulled downwardly by the sucker bar, as above described. In operation periodicals are arranged on the feed chains which 125 travel along the table 157, due to rotation of the chain feed shaft, and place the periodicals on the feed shelf where they are propelled inwardly by the feed rollers, it being assumed that a printing device has been selected for printing and is in the proper printing position. The pneumatic suckers then pull the forward end portion of the bottom periodical downwardly between the feed rollers and the gripper rollers. The finger bar rocks forwardly and the finger bar 130 fingers prevent more than one periodical from 135 140 145 150 155 160 165 170 175 180 185 190 195 200

being fed. Simultaneously with the movement of the finger bar the gripper roll rocker reciprocates and the gripper rollers clamp the periodical between the gripper rollers and the feed rollers and the periodical is fed onto traveling belts, to be described, and is carried to printing position and then off the frame. The machine will then have gone through one cycle of operation and is again ready to feed and print another periodical.

10 If, however, the selector mechanism, to be described, is not functioning, or a printing device is not in printing position, or certain printing devices not to be printed are fed into the machine, the selector mechanism will operate to shut off the suction in the sucker bar and will move the finger bar fingers to obstruct the feeding end of the machine so that no periodicals will be fed into the machine. The belt conveyor, referred to, comprises shafts 19 and 70 and shafts 71 and 72. Rollers 73 over which endless belts 74 are directed are mounted on these shafts and movement is imparted thereto from the belt roller shaft 19, the roller 73 on the shaft 19 being fast thereto while the other rollers are rotatably mounted on their respective shafts. The belts 74 carry the periodical to printing position and after it is printed they carry it beyond the machine to a suitable table or receptacle (not shown). Suitable belt tighteners 75 take up the slack in the belt 74. A longitudinal cam shaft 76 (Fig. 2) on the rearward side of the frame receives motion from the drive shaft 2 through bevel gears 77 and 78. The platen 82 (Fig. 9) is carried by a platen arm shaft 83 mounted in the frame of the machine and is operable by cams provided on the shaft 76, this arrangement being shown in Letters Patent No. 1,481,860, patented January 29, 1924. A printing device magazine 85 is arranged at the rear of the machine medially thereof into which printing devices are introduced which are withdrawn therefrom and fed into printing position by intermittently operated feed chains 87 which move a printing device through selecting position before moving it into printing position. The feed chains are arranged in parallel relation and are directed about sheaves 90 and about sprockets 91 to be driven thereby. The sprockets are fixed to a shaft 92 (Fig. 6) and one of the sprockets has a number of projecting pins 93 thereon. A pawl 94 carried by an arm 95 successively engages these pins to turn the sprockets and thereby impart a step-by-step movement to the chains. The arm 95 is part of a rocker 96 and is actuated through suitable connections by cams on shaft 76. (See Fig. 9.) After the printing devices have been moved through printing position they are engaged by a suitable packer rocker 102 (Fig. 1) so timed and constructed that as soon as the printing device falls into a storage drawer supported below the printing device guideway the packer urges the device and the preceding devices rearwardly in the drawer to permit the passage of succeeding printing devices therewith. An arm secured to rocker 96 extends upwardly therefrom and connects with a selector pin bar 104 (Fig. 9) and during reciprocating motion of the rocker 96 moves the pin bar up and down to operate the cooperating parts of the selecting mechanism which may be of the character disclosed in Patent No. 1,503,822, patented August 5, 1924, and reference may also be made to Patents Nos. 1,082,505, patented December 30, 1913, and 1,209,414, patented December 19, 1916. A bar 105 (Fig. 2) pivotally mounted on the frame carries an upwardly extending arm 105' having a cam roller 106 thereon (Figs. 1a and 2). This roller rides on a cam 107 fast on driving shaft 2. One end of a spring 105'' is fastened to bar 105 and the other end is fast to the frame to thereby hold roller 106 against cam 107. The forward end of bar 105 carries a clutch member 108 (Fig. 1) engageable with a clutch member 109 (Fig. 1) fast on the rod 110 communicating with clutch 10 on flywheel 3. When the clutch members are engaged as shown in Fig. 3 the machine is in operating position, but when disengaged the pawl 6 is held from engagement with the flywheel and therefore the machine is inoperative. When the roller 106 rides onto the low portion of cam 107 it moves bar 105 outwardly and also moves the clutch members 108 and 109 out of engagement, thereby lifting the rod 110 and disengaging the clutch 10. The arm 8 disengages the pawl 6 from the slot in the drive shaft 2 thereby interrupting operation of the machine and the drive shaft will operate idly. However, this condition is only desired when no printing device is to be fed. Therefore means are provided to hold the clutches in engagement when the printing device is operating properly. A rod 111 (Fig. 1) connects bar 105 to pivoted finger 112 (Fig. 9) arranged on the periodical rack. When the printing devices are arranged in the magazine, the finger 112 acts through rod 111 to move bar 105 outwardly, thereby holding the cam roller 106 from movement into the low spot of cam 107 and thus the clutch members 108 and 109 are held in engagement with each other. When there are no printing devices in the magazine the roller will move onto this low spot to disengage the clutch members and interrupt operation of the machine. When a printing operation is being performed the periodical or other article being printed is held against movement and this is attained by providing stops 113 and 114 (Fig. 1) to hold the periodical against movement with the belt during a printing operation. The stop 114 holds the periodical being printed against movement and the stop 113 prevents the succeeding periodical from being fed against or on top of the one being printed. Each stop comprises fingers 115 projecting from a bar 116 rigidly connected to a rod 117 supported in suitable bearings 118 carried by the frame and is provided with arms 119 (Fig. 3) supporting rollers 119 which lightly rest on the article to insure movement thereof with the belt. An arm 121 (Fig. 5) secured to the end of the bar 116 carries a roller 122 that is loosely mounted thereon. This roller rides on a cam 123 fast on longitudinal shaft 124 driven from shaft 19 through gears 125 and 126. When the rollers 122 ride onto the low portion of the cams the stops 113 and 114 fall downwardly by their own weight. When the rollers move onto the high portion of the cams the stops are raised and when in this position the periodicals are free to be moved by the belt 74. The selecting mechanism of this machine operates in the manner described in the patents previously referred to, to determine or select some printing devices to be printed while others are, as it is termed, skipped. When a printing device is skipped a periodical is not fed into printing position and thus the periodicals are prevented from passing through the machine without receiving a printing impression. Furthermore, means are provided whereby the failure of a periodical to feed into printing position will prevent the discharge of a printing device from printing position that

has been determined to be printed until a periodical moves into printing position. A rod 127 (Fig. 6) is connected at one end to an arm 127' on a rod 127'' which extends transversely in the frame. The other end of the rod 127 is connected to an angle lever 227 pivoted at 227' on the frame and adapted to engage a pin 227'' on pawl 94 for releasing the pawl from pin 93 on sprocket 91. A spring 128' attached to the arm 127' and to the frame normally holds these parts in position with the pawl 94 out of operative relation to the pins 93 on the sprocket, but when a periodical is fed to printing position it will depress a roller 129, which is mounted on the arm 128 and projects up through an opening 130 in the table 130' of the machine, and the rod 127 is thus shifted to the right (Fig. 6) and the pawl 94 is then permitted by the angle lever 227 to engage one of the pins 93 for operating the printing device feed. In the absence of a periodical for depressing the roller 129, the feed pawl 94 will be held in inoperative position so that the printing device feed will not operate and this is desirable because a printing device to be printed should not be discharged from printing position until an impression has been taken therefrom. For insuring proper engagement of the periodical with the release roller 129 a double roller 134, carried by a rod 133 on a support 132 on the frame, is arranged over the opening 130 in the table. When there is no periodical present under the rollers 134 the release roller 129 will be projected by the spring 128' through the opening 130 in the table and between the rollers 134, as shown in broken lines in Fig. 6, and the feed pawl 94 will then be in inoperative position; but when a periodical is fed beneath the rollers it will force the release roller down against the tension of its spring 128' and cause the printing device feed to operate. A handle arm 131 is connected to the arm 127', which is in the form of a casting mounted on the rod 127'' and forming a support for the arm 128 so that the printing device feed control may be operated manually when desired. This handle also functions as a counterweight to supplement the spring 128'. The handle arm 131 has a roller 135 thereon which rides on a cam 136 fastened on shaft 124. When the roller rides onto the low portion of the cam 136 the wheel 129 is free to rise through the slot 130 and when the roller is on a high portion of the cam the wheel 129 is held downwardly. This arrangement permits a printing device to pass to printing position where it is retained for a printing operation. A bar 137 at the left hand end of the machine (Fig. 2) is similar to the stops 113 and 114. This bar serves to retard the movement of the periodical onto the receiving table and afford sufficient pressure to allow the periodical to be propelled by the belts 74. To prevent a periodical from being fed to printing position when a printing device is to be skipped a yoke 138 (Fig. 11) is pivoted to the frame and is operated by a rod 139 connected with selector pin bar 104. When the selector pin bar is operated by a printing device to be skipped, the yoke 138 is reciprocated. A bell crank 139' pivotally mounted on the frame carries a roller 140 which contacts with an edge of the frame and during reciprocation of the yoke this bell crank is moved. An arm 141 of the bell crank is connected to a rod 142 communicating with the arm of the pneumatic valve 66. Movement of the arm 141 causes rod 142 to move longitudinally and prevents reciprocation of the arm 69 thereby shut-

ting off suction in the bar 51 to prevent the bar from drawing a periodical into the machine. A rod 143 is connected to the arm 141 and is operated in the same manner as rod 142 and prevents reciprocation of the finger bar 170. When the finger bar is stopped it will be in the position shown in Fig. 3 and periodicals will be prevented from feeding. The periodicals travel in suitable guides fastened to the top of the frame to assure proper positioning thereof relative to the platen and also to assure proper orientation during a printing operation.

While I have illustrated and described a selected embodiment of my invention, it is to be understood that this is capable of variation and modification and I therefore do not wish to be limited to the precise details set forth but desire to avail myself of such changes and alterations as fall within the scope of the following claims:

We claim:

1. In a printing machine having a printing position and comprising a frame having a stack of magazines and a stack of printing devices supported thereon, means for feeding the printing devices one at a time into printing position, selector means for selecting certain of the printing devices to be printed and other of the printing devices to be skipped, means for feeding the magazines one at a time from the stack of magazines to printing position and comprising feeding means spaced from but juxtaposed to the stack of magazines, carrying means movable between the stack of magazines and the feeding means to carry a magazine from the stack to the feeding means, retaining means for preventing withdrawal of more than one magazine from the stack, and means operated by the selector means for controlling the operation of the feeding means, carrying means and retaining means.

2. A printing machine comprising a frame 115 having a stack of magazines and a stack of address printing devices supported thereon, means for advancing the printing devices one at a time from the bottom of the stack to printing position, selector means for selecting certain printing devices to be printed and other printing devices to be skipped, means for feeding the magazines one at a time from the bottom of the stack to printing position and comprising a feed roller shaft supported below the forward end of the stack, a feed roller on said shaft engaging the under side of the bottom magazine adjacent the forward edge thereof, a gripper roller shaft spaced from the feed roller shaft and gripper roller on the gripper roller shaft, suction means movable between said shafts to engage the bottom magazine in the stack between its forward edge and the feed roller and to pull the forward marginal edge portion of the bottom magazine down and partly around the feed roller, means for moving the gripper roller to press the magazine against the feed roller for feeding the magazine away from the stack, a finger normally engaging the bottom of the stack in front of the feed roller, means for moving the finger away from the stack to permit operation of the suction means and then to move the finger back in engagement with the stack to permit feeding of the bottom magazine without affecting other magazines in the stack, and means operated by the selector means for controlling the operation of the suction means, the gripper roller and the finger.

3. A printing machine having a printing position and comprising a frame having a stack of magazines and a stack of printing devices sup-

- ported thereon, means for feeding the magazines and means for feeding the printing devices one at a time to and away from printing position, and means for disabling the printing device feed 5 upon failure of the magazine feed to feed a magazine and comprising a safety device projecting in the path of movement of the magazines in a position between the magazine supply and printing position, and means independent of the means for feeding magazines to insure engagement of a magazine with said safety device. 80
4. A printing machine having a printing position and comprising a frame having a stack of magazines and a stack of printing devices supported thereon, a table having an opening therein, means for feeding the magazines one at a time over the table to printing position, means for feeding the printing devices one at a time to and away from printing position, a roller beneath the 10 table, means beneath the table connected with the printing device feed for moving said roller up through the opening in the table in the path of a magazine, said roller being engageable by a magazine to control the printing device feed to disable it in the absence of a magazine, and means independent of the means for feeding magazines to insure engagement of a magazine with said safety device. 90
- 20 5. A printing machine having a printing position and comprising a frame having a stack of magazines and a stack of printing devices supported thereon, a table, means for feeding the magazines one at a time over the table to printing position, means for feeding the printing devices one at a time to and away from printing position, there being an opening in the table, a roller beneath the table, and means beneath the table connected with the printing device feed for moving said roller up through the opening 105 in the table in the path of a magazine, said roller adapted to be operated by a magazine to operate the printing device feed and to operate in the absence of a magazine to disable the printing device feed, and means above the table and independent of the means for feeding magazines and engaging the magazine to make it cooperate with said roller. 110
- 30 6. A printing machine having a printing position and comprising a frame having a stack of magazines and a stack of printing devices supported thereon, means for feeding the magazines and means for feeding the printing devices one at a time to and away from printing position, a table on the machine having an opening therein, a pair of rollers arranged in spaced relation above the table adjacent said opening, a roller supported below the table, means for projecting the roller up through the opening in the table and between said spaced rollers, and means operated by said roller for controlling the printing device feed, said roller being depressed by a magazine beneath the spaced rollers for enabling the printing device feed to operate and said roller being held in elevated position in the table opening when a magazine is not present and disabling the printing device feed. 125
- 40 7. A printing machine comprising in combination, a frame, a driving shaft, a cam shaft, gears communicating with said shafts to drive the cam shaft, a table adjacent said frame, a chain feed shaft supported by said table, chains on said table and operated by the chain feed shaft for carrying magazines to the machine, a ratchet fixed on the last-named shaft, a bell crank loosely mounted on the chain feed shaft, means connected with 130
- 50 the cam shaft for reciprocating the bell crank, a pawl on said bell crank to engage said ratchet for operating the chain feed shaft, a feed control rocker, means on the cam shaft for reciprocating said rocker, a cam on said chain feed shaft and controlled by the feed control rocker for controlling the operation of the ratchet pawl, a reciprocating finger bar, fingers on said bar for preventing more than one magazine from being fed at one time, a gripper roller, means connecting the gripper roller and the cam shaft for reciprocating the gripper roller, a feed roller, means for operating the feed roller, a sucker bar for disposing a magazine between said rollers for feeding into the machine, means for reciprocating the sucker bar, means for feeding printing devices one at a time to printing position in the machine, means for selecting certain printing devices to be printed, and means controlled by the selector means for preventing the operation of the feed control 135 rocker and the sucker bar. 140
- 60 8. A printing machine comprising, in combination, a frame, a driven cam shaft supported by said frame, a table adjacent said frame, a chain feed shaft supported by said table, chains on said table and operated by the chain feed shaft for carrying magazines to the machine, a ratchet fixed on the last-named shaft, a reciprocating bell crank loosely mounted on the chain feed shaft, a pawl on said bell crank to engage said ratchet for operating the chain feed shaft, a reciprocating feed control rocker, a cam on said chain feed shaft and controlled by the feed control rocker for controlling the operation of the pawl on the ratchet, a reciprocating finger bar operated by the cam shaft, fingers on said bar for preventing more than one magazine from being fed to the machine at one time, a reciprocating gripper roller controlled by the cam shaft, a feed roller, a reciprocating sucker bar operated by the cam shaft, means for causing a suction in said bar upon one movement of the bar for causing a magazine to be placed between the rollers and for shutting off the suction upon reverse movement of the bar to release the magazine and allow it to pass to printing position in the machine, means for feeding printing devices one at a time to printing position, means for selecting certain printing devices to be printed, and means controlled by the selector means for preventing the operation of the feed control rocker and the sucker bar. 145
- 70 9. A printing machine comprising, in combination, a frame, a driven cam shaft supported by said frame, a table adjacent said frame, a chain feed shaft supported by said table, chains on said table and operated by the chain feed shaft for carrying magazines to the machine, a ratchet fixed on the last-named shaft, a reciprocating bell crank loosely mounted on the chain feed shaft, a pawl on said bell crank and reciprocated thereby, a reciprocating feed control rocker, a cam on said chain feed shaft controlled by the feed control rocker for operating the pawl on the ratchet, a reciprocating finger bar, fingers on said bar for preventing more than one magazine from being fed at one time, a reciprocating gripper roller, a feed roller, means for operating the feed roller, a reciprocating sucker bar for causing a magazine to be placed between said rollers for feeding the magazine to the machine, means for feeding printing devices one at a time to printing position, means for selecting certain printing devices to be printed, and means controlled by the selector means for preventing 150

magazines from being fed when a device selected for printing is not in printing position or when printing devices not selected for printing are being fed.

5 10. A printing machine comprising in combination a frame, a driven cam shaft supported by said frame, a table adjacent said frame, a chain feed shaft supported by said table, a plurality of chains on said table and operated by the chain feed shaft for carrying magazines to the machine, a ratchet fixed on the last-named shaft, a reciprocating bell crank loosely mounted on the chain feed shaft, a pawl on said bell crank and reciprocated thereby, a feed control rocker, 10 15 means for reciprocating said rocker, a cam on said chain feed shaft controlled by the feed control rocker for operating the pawl on the ratchet, a reciprocating finger bar, fingers on said bar for preventing more than one magazine from being 20 fed into the machine at one time, a reciprocating

gripper roller, a feed roller, means for operating the feed roller, a sucker bar, means for reciprocating the sucker bar, means for causing a suction in said bar upon one movement of the sucker bar for causing a magazine to be placed between the rollers, means for shutting off the suction upon reverse movement of the bar and to release the magazine and allow it to pass to printing position in the machine, means for feeding printing devices one at a time to printing position, means for selecting certain printing devices to be printed, and means controlled by the selector means for preventing magazines from being fed into the machine when a printing device selected for printing is not in printing position or when printing devices not selected for printing are being fed in the machine.
